US0D1082984S

(12) **United States Design Patent** (10) Patent No.: **US D1,082,984 S**
(45) Date of Patent: ** Jul. 8, 2025

(54) **PUTTER HEAD**

(71) Applicant: **Topgolf Callaway Brands Corp.**,
Carlsbad, CA (US)

(72) Inventors: **Tim Reed**, Carlsbad, CA (US); **Eric Stubben**, Encinitas, CA (US); **Joseph Toulon**, Vista, CA (US); **Johnny Thompson**, Carlsbad, CA (US); **Jacob Davidson**, Carlsbad, CA (US); **Keith Kingston**, Oceanside, CA (US); **Thomas Vu**, Westminster, CA (US); **Cody Hale**, Carlsbad, CA (US); **Steve Mata**, Carlsbad, CA (US); **Seamus Sweeney**, Chessington (GB); **Sean Toulon**, Vista, CA (US)

(73) Assignee: **Topgolf Callaway Brands Corp.**,
Carlsbad, CA (US)

(**) Term: **15 Years**

(21) Appl. No.: **29/942,007**

(22) Filed: **May 13, 2024**

(51) LOC (15) Cl. **21-02**

(52) U.S. Cl.

USPC **D21/743**

(58) **Field of Classification Search**

USPC D21/736-746, 759
CPC A63B 53/00; A63B 53/04; A63B 53/007;
A63B 53/065; A63B 53/0487; A63B
60/00; A63B 60/46

(57) **CLAIM**

The ornamental design for a putter head, as shown and described.

DESCRIPTION

FIG. 1 is a front elevation view of a putter head;

FIG. 2 is a rear elevation view thereof;

FIG. 3 is a top plan view thereof;

FIG. 4 is a bottom plan view thereof;

FIG. 5 is a heel-side elevation view thereof;

FIG. 6 is a toe-side elevation view thereof; and,

FIG. 7 is a top perspective view thereof.

The broken lines shown in the drawings form no part of the claimed design.

1 Claim, 5 Drawing Sheets
